UNITED STATES PATENT OFFICE.

ALFRED AARON PLOUGH, OF MEMPHIS, TENNESSEE, ASSIGNOR TO PLOUGH CHEMICAL COMPANY, OF MEMPHIS, TENNESSEE, A CORPORATION OF TENNESSEE.

COMB.

Application filed September 9, 1920. Serial No. 409,217.

To all whom it may concern:

Be it known that I, ALFRED A. PLOUGH, a citizen of the United States, residing at Memphis, in the county of Shelby and State of Tennessee, have invented certain new and useful Improvements in Combs, of which the following is a specification.

The object of this invention is to provide an improved comb for use by hair-dressers.

Referring to the accompanying drawings, which are made a part hereof and on which similar reference characters indicate similar parts.

Figure 1 is a view of my comb in elevation, and

Figure 2 a section on line 2—2 of Figure 1.

In the drawings reference character 1 indicates a comb having a handle 2 which may be of wood, the body of the comb being preferably made of pure yellow brass without any appreciable alloy of other metal. The comb has a back 3 somewhat curved from front to rear along its upper line and having its corners rounded off as seen in Figure 2. The back of the comb is thus rendered smooth and has no sharp corners or edges to break the hair.

The teeth 4 are so formed as to describe with the body a curve at the one side of the comb at 5, as seen at the left in Figure 2, and the other side is formed in a curve at 6, as by grinding or casting which also takes off a portion of the back of the comb at 6. The teeth as seen in Figure 1 are all equally spaced from top to bottom so as to avoid wedging the hair into a V-shaped notch at the junction of the teeth with the back as in many combs whereby the hair is liable to be broken or pulled out.

Hairdressers' combs of this type are intended to be used in straightening hair which is curly or kinky, by heating the comb and drawing it through the hair. By repeated combing it will become straightened and will remain so for some time. It is important that the comb retain its heat for a long time and especially that it re-

main at its most effective temperature for a long time and this end is attained by making the metallic portions of pure brass only. The nature of the hair operated on, and the fact that such hair is often matted and dirty renders it necessary to use every precaution to minimize breaking, tearing and uprooting of the hair. The even spacing of the teeth, the curving of the back, from one end to the other, the rounding of the corners of the back to a point where the angles practically disappear, the smooth curve of the rear or left side of the comb as seen in Figure 2, and the obtuse angle formed between the cut away portion 6 of the back and the portions 7 between the bases of the teeth all play a part to make the action of the comb smooth and easy, and prevent deleterious effects on the hair.

Having thus fully described my said invention, what I claim as new and desire to secure by Letters Patent, is:

A comb or tool for use in straightening curly or kinky hair comprising a body portion of pure brass, and a handle of heat insulating material, said body portion being formed curved along the upper line of its back and rounded at its corners, said comb being also curved in a direction cross-wise thereof, the front of the comb being concaved on a greater curvature than the convex curvature of the back and the convex curvature of the front extending throughout the length of the teeth and a portion of the back behind the base of the teeth, whereby a tool of the character described is provided adapted to readily slide through the hair and also one adapted to maintain the temperature desired, all as substantially set forth.

In witness whereof, I have hereunto set my hand and seal at Memphis, Tennessee this 7th day of September, A. D. nineteen hundred and twenty.

ALFRED AARON PLOUGH. [L. s.]
